UNITED STATES PATENT OFFICE.

JOHN W. RUSSEL, OF MARIETTA, PENNSYLVANIA.

COMBINATION DRAIN BOARD AND TUB COVER.

Application filed January 3, 1927. Serial No. 159,149.

My invention is a combined drainboard and tub cover and it consists in the combinations, constructions and arrangements herein described and claimed.

5 An object of the invention is the provision of a combination drainboard and tub cover which is stamped of steel in a single piece and which therefore combines lightness in weight with relatively great strength and 10 durability.

A further object of the invention is the provision of a combination drainboard and tub cover having hanger means whereby it can be removably supported over a tub below 15 the level of the edge of the tub so that any moisture that falls onto the device will drain therefrom below the level of the tub rim or edge.

Other objects and advantages of the invention will be apparent from the following 20 description, considered in conjunction with the accompanying drawings, in which:

Figure 1 is a perspective view of a laundry tub equipped with a combination drainboard 25 and cover embodying the invention,

Figure 2 is a fragmentary longitudinal vertical section through the tub and the combination drainboard and cover, and

Figure 3 is a fragmentary transverse 30 vertical section through the tub and the combination drainboard and cover.

In the drawings, the numeral 1 designates a laundry tub which is of the usual double or two-compartment type, being provided 35 intermediate its length with a transverse partition 2 which terminates at its upper edge below the edge of the body of the tub, thus producing the adjacent compartments 3.

A combination drainboard and cover for 40 either of the tub compartments preferably is formed of steel in one piece by stamping and comprises a plate-like body 4 having a continuous marginal flange or apron 5 and sloping slightly from its side edges toward 45 its longitudinal median line. The body 4 of the device is formed with the marginal portion thereof raised to produce the transversely rounded ridge or bead 6 which extends completely across one end of the body 50 4, along the side edges of the body 4, and along the other end of the body 4 from the sides of the body for part of the distance to the longitudinal median line of the body 4, the ends of the bead 6 being turned outwardly at the second end to the body 4, thus 55 producing the drain spout 7.

The body of the device also is formed with the grooves 8 in its upper face which extend in the general direction of length of the body 4 for the greater part of the 60 length of the latter and slope toward the spout 7. The grooves 8 may be supplemented by lateral oblique grooves as at 9 which also slope toward the spout 7 and the grooves 8 and 9 all converge toward 65 the spout 7 and discharge into or through the latter.

The upper face of the device may be suitably enameled or otherwise finished.

The device is adapted to fit in the upper 70 part of one of either of the tub compartments 3 so that the end portion of the device that is provided with the spout 7 rests on the partition 2, the body of the device being supported on the tub body by the end 75 hanger hooks 10 and the side hanger hooks 11. Each of the hanger hooks 10 is adapted to hook over the upper edge of an end wall of the tub body and has the end portion of its shank flattened at 12 and secured flat- 80 wise to the adjacent end portion of the apron 5 by a fastening device 13. Each of the side hanger hooks 11 is adapted to hook over a side wall of the tub body and has the extreme end portion of its shank flattened 85 and formed to produce a reversely curved supporting hook 14 for the reception of the edge of a side portion of the apron 5.

It is obvious that the device may be disposed in a single compartment tub or other 90 receptacle equally as well as in the double compartment tub exhibited in the drawings.

From the foregoing description of the various parts of the device, the operation thereof may be readily understood. The 95 device can be instantly removed from applied position on a tub and as quickly re-placed thereon.

Obviously, the invention is susceptible of embodiment in forms other than that which 100 is illustrated in the drawings and I therefore consider as my own all such modifications and adaptations thereof as fairly fall within the scope of the appended claims.

I claim:

1. A combination drainboard and tub cover comprising a slightly dished rectangular body portion having slightly raised marginal edges and an apron depending therefrom, hanger hooks having their shanks 110 attached to an end portion of said apron and being adapted to hook over the upper

edge of the adjacent end wall of a tub, and other hanger hooks adapted to hook over the upper edges of side walls of the tub and having reversely curved hooks at the extremities of their shanks for the reception of edge portions of the side members of said apron.

2. A combined drainboard and tub cover stamped in one piece of steel to produce 10 a plate like body having a depending marginal apron and a raised marginal portion extending completely across one end of the body, along the sides of the body, and inwardly along the other end of the body from 15 the sides of the body part of the distance to

the longitudinal median line of the body and then outwardly, thus forming a drain spout at the second end of the body, said body sloping from its side edges toward its longitudinal median line and having grooves in its upper face converging toward said spout, and having hanger hooks adapted to hook over the upper edge of the adjacent end wall of a tub, and other hanger hooks adapted to hook over the upper edges of side walls of the 25 tub and having reversely curved hooks at the extremities of their shanks for the reception of edge portions of the side depending members of said marginal edge.

JOHN W. RUSSEL.
